UNITED STATES PATENT OFFICE.

JOHN L. MASON, OF DAVENPORT, IOWA.

SHIFTING SEAT FOR VEHICLES.

SPECIFICATION forming part of Letters Patent No. 398,419, dated February 26, 1889.

Application filed October 1, 1888. Serial No. 286,936. (No model.)

To all whom it may concern:

Be it known that I, JOHN L. MASON, a citizen of the United States, residing at Davenport, in the county of Scott and State of Iowa, have invented a new and useful Improvement 5 in Shifting Seats for Vehicles, of which the following is a specification.

My invention relates to that class of vehicles having two or more seats, and my object is to 10 arrange the seat so it may be temporarily moved forward while occupied to allow additional space between it and the next rear seat to accommodate persons getting into such seat, and thereafter moved back to its normal position. I attain these objects by the mechanism 15 illustrated in the accompanying drawings, in which—

Figure 1 is a side perspective view of a two-seated surrey carriage-body, its panel broken 20 away under the front seat. Fig. 2 is a front view of one of the seat-carriers and its sill-sockets. Fig. 3 is a vertical sectional view of the seat-frame and seat-carriers. Fig. 4 is a detail view of one method of attaching the seat-carrier to the under side of the seat. Fig. 5 is a vertical sectional view of the seat-frame and 25 seat-carrier attached to the under side of the seat by the method illustrated in Fig. 4, and Fig. 6 is a detail view of one method of attaching a stop to the longitudinal bars connecting the posts of the seat-frame as supports for the seat-carriers to rest against.

Similar letters and figures refer to similar parts throughout the several views.

35 A represents the side panels of a surrey carriage-body; B, its longitudinal sills; C, its seats, and c the backs of such seats. 1, 2, 3, and 4 represent seat-posts framed to the sills. 5 and 6 are longitudinal bars framed to the 40 top of said posts, and 7 and 8 are cross-bars attached to said posts. Seat C has its support upon said frame.

The seat-carrier is preferably made of steel, 45 although other material may be used; and it consists of two vertical rods, 9 and 10, the bottom of each bent in the form of an elbow, extending in a direction crosswise of the vehicle-body, such parts screw-threaded, as at 12 and 13, and the tops of such rods connected by the horizontal cross-rod 14. I prefer to make the seat-carrier of one piece of

steel; but when made for the trade generally, as carriage-bodies may vary in width, it may be made in two parts, which thereafter can be welded together, as at *xx*, to insure the proper 55 width between the vertical rods.

Sill-sockets 15 are perforated crosswise, having interior screw-threads, into which the parts 12 and 13 of said seat-carrier are screwed, and such sill-sockets are also perforated vertically to accommodate bolts or screws for attaching the same to sills B or the body of the carriage. Such screw-threads may be omitted in said sill-sockets and on said seat-carrier, and the parts 12 and 13 seated in said 60 perforations and secured therein by being headed or by other well-known means understood by any skilled mechanic.

Two seat-carriers are attached crosswise to the vehicle-body by hinging their parts 12 and 13 in sill-sockets 15 and attaching the latter to said sills B, and cross-rods 14 of each carrier are secured or hinged to two longitudinal parallel bars, each consisting of two parts, the upper, 16, and lower, 17, each having half-round grooves to accommodate and hinge cross-rod 14. Bars 16 and 17 are preferably 65 constructed of wood, secured together by screws or bolts. The under side of seat C is rigidly attached on the upper surface of bar 70 16 by means of screws or bolts. Openings or slots 18 are cut through cross-bars 7 and 8 to accommodate the ends of bars 16 when moved forward or backward, and such slots also form 75 supports for said bars and thereby said seat. 80

If desired, I can dispense with bars 16 and 17 and use staples 19 to hinge horizontal cross-rod 14 to the under side of seat C, securing 85 said staple thereto by screws or bolts. I prefer, however, the first-described mode of hinging, as it avoids the noise and rattle which usually take place when one piece of iron is hinged in another piece of iron. I prefer to attach a cross-beam, 20, preferably of wood, 90 crosswise and near the center of the seat-frame, to the under side of bars 5 and 6. Such cross-beam adds strength to the seat-frame, and its upper surface furnishes support to bar 17, thus supporting seat C, while its sides 95 act as stops for vertical rods 9 and 10 of the 100 seat-carrier when swung forward or backward. I can, however, dispense with such cross-beam

and attach to the under side of bars 5 and 6 a double elbow, 21, which likewise will form a stop for said rods 9 and 10 of the seat-carrier. So, too, I can dispense with said cross-beam 5 20 and said stop 21. When the seat-carriers are moved forward or backward, it will be observed that by reason of the horizontal cross-rod of each being hinged to the under side of the seat, and the lower vertical rods of each 10 also being hinged crosswise to the longitudinal sills, both of said seat-carriers move together and parallel, and when the under side of the seat rests upon the top of the seat-frame such frame supports the seat and acts 15 as a stop, preventing the seat-carriers swinging farther in that direction. This is illustrated in Fig. 5. The under side of the seat C rests upon the seat-frame and is in its normal position; but by swinging the seat-carrier 20 forward it and seat C will occupy the position indicated by the dotted lines in said Fig. 5, and said seat will in that position be supported by said seat-frame, and which also acts as a stop by preventing the seat-carrier from 25 swinging farther forward.

I can dispense with sill-sockets 15 and with the screw-threaded parts of the seat-carrier. In such case the elbowed parts at 12 and 13 are plain rounded surfaces, and may be inserted 30 in suitable crosswise perforations in longitudinal sills B; but such perforations tend to weaken the sills, and when such sills are constructed of wood the perforations will become enlarged by use, tending to make the 35 seat-carrier unsteady; hence I prefer the use of sill-sockets. A device for accomplishing the same object, substantially, could be constructed by dispensing with the horizontal cross-rod 14 and the tops of rods 9 and 10, 40 hinged to the under side of seat C; but such construction would be objectionable, because such a seat-carrier would be unsteady. One of the chief functions of said horizontal cross-rod is to keep the vertical rods steady and 45 firm; hence such horizontal cross-rod is a material part of the structure.

I am aware that what are commonly known as "jump-seats" or "removable seats"—that is, seats which are folded or laid down upon 50 the floor of the carriage-body when not in use—are constructed by hinging the under side of the seat to the top of four posts, the bottom of each of which posts is hinged to the longitudinal sills or the floor of the carriage-body, and which posts, carrying the seat, may be freely swung in one direction to remove or 55 displace the seat, while suitable stops are provided to arrest their swinging too far in the opposite direction and to retain such posts 60 and seat in position for occupancy. The objects attained in such seats are entirely different from the objects I obtain by my device. In such construction the hinged posts and stops constitute the seat frame and support 65 for the seat. In my device the stationary frame constitutes the fixed support for the seat, while the hinged vertical rods, connected

at their upper ends by the horizontal cross-rod, constitute the means for sliding or shifting the seat from one position of support on 70 the stationary seat-frame to another position of support thereon, and only furnish support to the seat when it elevates it above the frame in moving it from one position to the other. In my device such shifting movement of the seat can be obtained through motion of the body of the person occupying it 75 without arising therefrom.

In the construction of carriage-bodies intended for two or more seats, both for strength 80 and symmetry, the body is shortened as much as can be and accommodates the seats with room for occupancy. In such construction the hind wheel is necessarily so far forward that a person, especially a lady, in getting into 85 the rear seat is apt to soil her dress from dirt upon the wheel. So, too, for ease and comfort, the backs of the seat are usually high and incline rearward, as shown in Fig. 1, and this renders it difficult for a person to enter 90 the carriage-body to occupy the rear seat. I seek to obviate these objectionable features by my improvements, and when my device is used the carriage-step for mounting to the rear seat may be set well forward of the rear 95 wheel upon the carriage-body.

In my construction lamp-irons for holding lamps may be rigidly attached to each side of the shifting seat; but I prefer to attach these irons to the sides of the vehicle-body and 100 have same also act as supports for the top standards where a top or cover is used.

I am aware that some vehicle-bodies are constructed with a cut-under or wheel-house, and in such case my device may be used by 105 modifying the parts, all of which can be accomplished by a skilled mechanic without departing from the scope of my invention.

Many modifications and changes in the form of my device can be made without departing 110 from the scope of my invention—as, for instance, the side panels underneath the sliding seat may be split longitudinally and the upper portion rigidly attached to such sliding seat, so as to move with it, while the lower 115 portion remains stationary.

What I claim as new, and desire to secure by Letters Patent, is—

1. In a vehicle-body provided with two or more seats for constant use, the combination 120 of the permanent seat-frame with the hinged seat-carriers and seat hinged thereto, for the purpose of temporarily increasing the distance between adjacent seats by shifting such seat from one position of support upon said frame to another position of support thereon, substantially as described.

2. In a vehicle-body, a seat hinged upon its under side to two parallel cross-bars, the ends of said cross-bars bent downward, each 130 terminating in elbows crosswise to said vehicle-body and hinged thereto, in connection with a permanent seat-frame attached to said body and arranged to support said seat when

such horizontal bars are swung forward or backward, so the point of hinging with said seat is not in the same vertical line with the point of hinging said elbows to the body of said vehicle, substantially as described.

5. In a vehicle-body, the combination, with a permanent seat-frame attached thereto, of a seat hinged to seat-carriers, such carriers hinged in sill-sockets having threaded aper-

tures to receive the threaded ends of the carriers for the purpose of swinging the seat from one position of support upon the frame to another position of support thereon, substantially as described.

15 6. The herein-described seat-carrier, consisting of two horizontal and parallel cross-bars, their ends bent downward, each end terminating in elbows of similar direction of extension as said horizontal cross-bars, hinged

20 to the body of a vehicle, with a seat hinged upon the two horizontal and parallel cross-bars, substantially as described.

5. The herein-described seat-carrier, consisting of two horizontal and parallel cross-bars, their ends bent downward, each end 25 terminating in screw-threaded elbows of similar direction of extension as said horizontal cross-bars, each hinged in the threaded aperture of a sill-socket, with a seat hinged upon the two horizontal and parallel cross-bars, 30 substantially as described.

6. In a vehicle shifting seat, two L-shaped rods, their tops connected by a horizontal cross-rod, their bottoms hinged to opposite sides of the vehicle-body to permit the cross-rod to swing over forward and backward, arranged in pairs at suitable distances apart, and a seat hinged at a similar distance to each of said horizontal cross-rods, substantially as described.
